[57] CLAIM

The ornamental design for a notebook computer housing, as shown and described.

DESCRIPTION

FIG. 1 is a top perspective view of the notebook computer housing showing my new design;

FIG. 2 is a side elevational view thereof;

FIG. 3 is a front elevational view thereof;

FIG. 4 is a back elevational view thereof;

FIG. 5 is a bottom plan view thereof;

FIG. 6 is a top perspective view thereof in an open position;

FIG. 7 is a top plan view thereof in an open position;

FIG. 8 is a top perspective view of a second embodiment thereof;

FIG. 9 is a side elevational view thereof;

FIG. 10 is a front elevational view thereof;

FIG. 11 is a back elevational view thereof;

FIG. 12 is a bottom plan view thereof;

FIG. 13 is a top perspective view thereof in an open position; and,

FIG. 14 is a top plan view thereof in an open position.
